US0D1064571S

(12) **United States Design Patent** (10) **Patent No.:** **US D1,064,571 S**
(45) **Date of Patent:** **** Mar. 4, 2025**

(54) **LID KIT**

(71) Applicant: **NINGBO HAOLEI INTELLIGENT TECHNOLOGY CO., LTD.**, Yuyao (CN)

(72) Inventor: **Bin Li**, Yuyao (CN)

(73) Assignee: **NINGBO HAOLEI INTELLIGENT TECHNOLOGY CO., LTD.**, Yuyao (CN)

(**) Term: **15 Years**

(21) Appl. No.: **29/846,700**

(22) Filed: **Jul. 19, 2022**

(51) LOC (15) Cl. **09-07**

(52) U.S. Cl. **USPC D7/629**

(58) **Field of Classification Search**

USPC D3/302, 321; D7/601, 602, 629,
D7/701-703

(57) **CLAIM**

The ornamental design for a lid kit as shown and described.

DESCRIPTION

FIG. 1 is a perspective view of a first lid of a lid kit showing my new design shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the first lid where the first lid is in a first configuration of use; FIG. 10 is a perspective view of the first lid where the first lid is in a second configuration of use; FIG. 11 is a perspective view of a second lid of the lid kit shown separately for ease of illustration; FIG. 12 is another perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; FIG. 19 is a perspective view of the second lid where the second lid is in a first configuration of use; and, FIG. 20 is a perspective view of the second lid where the second lid is in a second configuration of use. The broken lines in FIG. 9-10 and FIG. 19-20 showing storage boxes depict environment and form no part of the claimed design. The broken lines in the drawings depict portions of the lid kit that form no part of the claimed design.

1 Claim, 20 Drawing Sheets
